A. E. PRESSON,
COLLAPSIBLE BATH TUB.
APPLICATION FILED MAY 21, 1914.

1,139,576.

Patented May 18, 1915.

UNITED STATES PATENT OFFICE.

ALFRED E. PRESSON, OF GLOUCESTER, MASSACHUSETTS.

COLLAPSIBLE BATH-TUB.

1,139,576.

Specification of Letters Patent. Patented May 18, 1915.

Application filed May 21, 1914. Serial No. 840,096.

To all whom it may concern:

Be it known that I, ALFRED E. PRESSON, a citizen of the United States, residing at Gloucester, in the county of Essex and State of Massachusetts, have invented certain new and useful Improvements in Collapsible Bath-Tubs, of which the following is a specification.

The present invention relates to a portable and collapsible infant's bath tub, and has for its object to provide a device of this character which embodies novel features of construction whereby it can be used interchangeably in connection with two sets of supporting members, one set of supporting members providing means for mounting the infant's tub upon a standard sized adult's tub, while the other set of supporting members provides a stand for holding the infant's tub in an elevated position above the floor.

A further object of the invention is to provide a collapsible infant's bath tub which can be compactly folded when not in use, which can be quickly set up in operative position, which can be shifted to any desired position upon the standard size adult's tub when mounted thereon, and which is simple and inexpensive in its construction.

With these and other objects in view, the invention consists in certain novel combinations and arrangements of the parts as will more fully appear as the description proceeds, the novel features thereof being pointed out in the appended claims.

For a full understanding of the invention, reference is to be had to the following description and accompanying drawing, in which:

Figure 1 is a top plan view of a collapsible infant's bath tub constructed in accordance with the invention, showing the same as mounted upon a standard sized adult's bath tub. Fig. 2 is a vertical transverse sectional view on the line 2-2 of Fig. 1. Fig. 3 is an enlarged detail view on the line 3-3 of Fig. 1. Fig. 4 is an enlarged perspective view of one of the guide members which are applied to the frame at opposite ends of the tub, one set of supporting arms being shown in position therein, and portions being broken away and shown

in section. Fig. 5 is a perspective view showing the tub as mounted upon a supporting frame which is interchangeable with the supporting arms shown by Figs. 1 and 2. Fig. 6 is a detail perspective view on an enlarged scale of the upper hooked end of one of the frame bars employed in constructing the frame shown by Fig. 5. Fig. 7 is a transverse sectional view through a modified construction of the double guide sleeve member.

Corresponding and like parts are referred to in the following description and indicated in all the views of the drawings by the same reference characters.

Specifically describing the present embodiment of the invention, the numeral 1 designates a main frame, and 2 a basin formed of heavy canvas or other flexible waterproof material and applied to the frame 1. The frame 1 may be formed of any suitable material such as wood, and may be of any desired shape or configuration, although in the present instance it is shown as rectangular in form. The edges of the waterproof fabric of which the basin 2 is formed may be folded around the sides of the frame 1 and secured thereto in any suitable manner. Owing to the flexible nature of the fabric from which the basin is formed it will be obvious that the basin or tub can be readily collapsed so as to occupy but a small amount of space when not in use.

Applied to each end of the main frame 1 is a metal strip 3 which has opposite sides thereof returned to provide the two longitudinally disposed and parallel guide sleeves 4, the edges of the returned sides overlapping each other at the middle of the strip 3 and being secured thereto by suitable fastening members 5. As shown upon the drawing these fastening members 5 are in the form of nails which pass through the three superposed thicknesses of metal and provide a means for securing the metal strip to the frame. As shown more clearly by Fig. 3, the edges of the waterproof fabric of which the basin or tub 2 is formed may be interposed between the metal strips 3 and the frame 1 so as to be held in position by the metal strips.

When it is desired to mount the infant's bath tub upon a standard sized adult tub such as is indicated by the numeral 6, a set of arms 7 is employed in connection with the double guide sleeve 4—4 at each end of the tub. Two of these supporting arms 7 are used at each end of the infant's tub, the said arms being slidably received within the respective guide tubes 4 and projecting laterally from opposite sides of the tub. The projecting ends of the arms are curved or slightly hooked as indicated at 7^a so as to fit over and engage the sides of the adult's bath tub 6. Some form of protective member such as the rubber tubing 8 may be applied to the curved or hooked ends 7^a of the supporting arms 7 to prevent the same from marring or injuring the finish upon the sides of the adult's bath tub 6. The supporting arms 7 are adapted to telescope freely in and out within the tubular guide sleeves 4 so that they can be caused to project any desired distance from the infant's bath tub and be properly adjusted to fit any size of adult's bath tub. It will also be obvious that the main frame 1 can be moved back and forth upon the supporting arm 7 so as to be adjusted in any desired position upon the adult's bath tub 6 relative to the sides thereof.

When an adult's bath tub is not convenient or when it may for any reason be desirable to support the infant's bath tub independently of the adult's bath tub, a supporting stand such as shown by Fig. 5 can be substituted for the supporting arms 7 previously described. This stand is composed of four supporting bars 9, two of which are arranged at each side of the tub. The upper ends of the supporting bars 9 are bent laterally or hooked at 9^a so as to be readily inserted within the end of the tubular guide sleeves 4. The pair of supporting bars 9 at each side of the tub cross each other and are pivotally connected at their point of intersection. It will also be observed that the two sets of crossed and pivotally connected supporting bars 9 at opposite sides of the tub are connected by a cross bar or tie rod 10 so as to hold the same together and prevent spreading thereof. The extremities of the bar 10 may pass through the intersecting members 9 and provide the pivotal connection between the same, and nuts 11 may be applied to the threaded ends of the member 10 to hold the supporting bars 9 in position thereon. When these nuts 11 are removed the supporting bars 9 and tie rod 10 can be disconnected from each other so as to be packed away in a very small amount of space. The supporting bars 9 and slides or arms 7 are adapted to be used interchangeably with each other, according to whether it is desired to mount the infant's bath tub upon an independent stand or to

mount it upon a standard sized adult's tub. Either set of supporting members can be very readily applied to the guide sleeves 4 and the infant's bath tub quickly set up in operative position. Furthermore, when the infant's bath tub is not in use, the flexible fabric basin portion thereof can be collapsed and the supporting members detached from the main frame so that the entire device can be very compactly packed.

A modified construction of the double guide sleeve member is shown by Fig. 7, in which the two guide sleeves 4^a 4^b are formed by using a seamless tube and flattening the same so that the opposite sides thereof are brought together at an intermediate point with longitudinal guide openings extending along the edges thereof. Under some conditions it may be preferable to construct the double guide sleeve in this manner, instead of using a flat plate and returning the edges thereof, as previously described.

Having thus described the invention, what I claim as new and desire to secure by Letters Patent, is:—

1. A portable and collapsible infant's bath tub including a main frame, a flexible waterproof basin applied thereto, plates applied to opposite ends of the main frame and each formed with double tubular guide sleeves, and supporting members adapted to detachably engage the guide sleeves.

2. A portable and collapsible infant's bath tub including a main frame, a flexible waterproof basin applied thereto, sheet metal plates applied to opposite ends of the frame and having opposite sides thereof returned to provide double tubular guide sleeves, and supporting members having end portions adapted to be loosely and detachably received within the said tubular guide sleeves.

3. A portable and collapsible infant's bath tub including a main frame, a flexible waterproof basin applied thereto, metal plates applied to opposite ends of the main frame and each formed with double tubular guide sleeves, supporting arms loosely received within the tubular guide sleeves so as to slide freely therein and projecting laterally upon opposite sides of the tub, the projecting ends of the supporting arms terminating in hook members adapted to be properly adjusted to engage the sides of an adult's bath tub.

4. A portable and collapsible infant's bath tub including a main frame, a flexible waterproof basin applied to the main frame and having the edges thereof folded around the sides of the frame, metal plates applied to the lower faces of the sides of the frame at opposite ends thereof so as to clamp the edges of the flexible waterproof basin against the frame, each of the plates being formed with a double set of tubular guide sleeves, and supporting arms loosely re-

ceived within the tubular guide sleeves so as to slide freely therein and project laterally upon opposite sides of the frame, the projecting ends of the supporting arms terminating in hook portions adapted to be properly adjusted for engagement with the sides of an adult's bath tub.

In testimony whereof I affix my signature in presence of two witnesses.

ALFRED E. PRESSON.
